UNITED STATES PATENT OFFICE

152,739

DESIGN FOR A CONDIMENT SHAKER

Dale Arden Rode, Arkansaw, Wis.

Application April 22, 1947, Serial No. 138,534

Term of patent 3½ years

(Cl. D44—22)

To all whom it may concern:

Be it known that I, Dale Arden Rode, a citizen of the United States, residing at Arkansaw, in the county of Pepin and State of Wisconsin, have invented a new, original, and ornamental Design for a Condiment Shaker, of which the following is a specification, reference being had to the accompanying drawing, forming part thereof.

I claim:

The ornamental design for a condiment shaker, as shown.

DALE ARDEN RODE.
